UNITED STATES PATENT OFFICE.

JOHN STEPHENSON, OF NEW YORK, N. Y.

CAR-BODY TRUSS.

SPECIFICATION forming part of Letters Patent No. 311,541, dated February 3, 1885.

Application filed July 14, 1884. (No model.)

To all whom it may concern:

Be it known that I, JOHN STEPHENSON, a citizen of the United States, and a resident of the city, county, and State of New York, have invented certain new and useful Improvements in Car-Body Trusses, of which the following is a specification.

My invention is a pedestal intended for that class of cars in which the sills are supported by trusses or girders arranged below the same, the said pedestal being constructed, as fully set forth hereinafter, so as to form part of the truss and permit the ready removal of the axles, wheels, springs, &c., without disorganizing the truss structure.

In the drawings, Figure 1 is a side view, in part section, of one of the sills and girders of an open car provided with my improved pedestal. Fig. 2 is a perspective view of the shell of one of the pedestals. Fig. 3 is a side view, partly in section, of one of the pedestals, showing the connections with the strut and stay-bar. Fig. 4 is an inverted plan of the pedestal. Fig. 5 is a perspective view of the wedge or bridge bar. Fig. 6 is a side view of a bridge-bar, showing a modification.

Summer or open cars being of light construction, and the frame-work being slight, and having but little strength, are dependent for their stiffness and rigidity upon the body and its supports.

Efforts to secure the desired stiffness of the body portion of such vehicles have proved to a great extent unsuccessful, mainly owing to the fact that the stiffening devices have been complicated and interfered with the frequent necessary changes and repairs of the wheels, axles, boxes, springs, &c., it being necessary in most instances to disorganize the entire truss structure when such changes or repairs are necessary, and the disorganization being attended generally with a permanent weakening of the structure.

To properly brace the body I combine with each sill a truss or girder, as set forth in my application for Letters Patent bearing even date herewith; and my invention consists of a pedestal adapted for use in such a structure. The said pedestal A has an elongated bed-plate, a, and at opposite edges of the latter are flanges b b, adapted to receive between them the sill B, the plate a having perforations c,

through which pass bolts d, that firmly clamp the pedestal to the sill. The flanges b b aid in retaining the pedestal in its position, and most effectively prevent it from twisting or turning, and also tend to remove the strains from the securing-bolts, and afford necessary stiffness to the bed-plate, preserving the truss in form when the wedge-bars are removed. 55

The pedestal is provided, as usual, with two jaws separated to receive between them the usual axle-box, and each consisting of a front plate, f, a back plate, f', and a union-bar or connecting-plate, g, the whole forming a light 60 but rigid and strong structure.

From each union bar or plate g project outward and downward lugs e, forming sockets or chambers x, of which the lugs e constitute the side walls, the inner edges of the lugs being 65 inclined or beveled to constitute bearing-faces y, for the purpose described hereinafter.

In the outer chamber, x, of each pedestal fits the eye end of a strut, D, which is held in place by a bolt, h, passing through the ears 70 and through the eye, and in the inner chamber of each pedestal fits the eye end of the stay-bar, E, secured by bolts h'.

To the lower part of the pedestal is adapted a wedge-bar, F, of suitable shape, (shown in 75 the present instance as curved downward, so as to permit ample play of the box,) and with flattened ends j, each with beveled edges to form inclined faces w, adapted to the beveled bearing-faces y. The wedge-bar F is slightly 80 longer than the space between the faces y y, so that when the said bar is placed between the said faces and lifted into contact with the union-bars it will tend to slightly spread or 85 separate the jaws of the pedestal, tighten the 90 truss or girder, and prevent any play or rattling or lost motion.

The wedge-bar may be connected to the pedestal and drawn upward by any suitable appliance. I prefer, however, to use bolts k, passing 95 through openings in the union-bars and in the ends of the wedge-bar, and provided with nuts i. Each end of the wedge-bar is preferably provided with a tongue, m, which extends between the lugs e, tending to hold the wedge-bar in its 100 position, and also in some cases affording a bearing against the end of the adjacent strut or stay-bar, so that the strains coming upon the said strut and stay-bar may be borne by the

wedge-bar, and not by the bolts h h' or the jaws of the pedestal. By this means I avoid all tendency of the jaws to be closed by pressure upon the end of the platforms, and at the same time brace the latter so as to resist strains tending to deflect its ends, while ready access may at any time be had to the axle-boxes, wheels, &c., upon unbolting and removing the wedge-bars without disorganizing the structure.

10 To secure increased strength and rigidity or a greater bearing-surface, each wedge-bar F , may be provided with a lug, n , having a shoulder, v , adapted to bear against the inner edge of the union-bar g .

15 I do not claim any of the features not hereinafter specifically claimed and which are also shown and claimed in my aforesaid application.

Without limiting myself to the precise construction and arrangement of parts shown, I claim—

20 1. A car-pedestal having front and rear walls connected by union-bars, carrying lugs forming the walls of intermediate chambers or sockets and extending below the pedestal, and having bearing edges or shoulders, substantially as and for the purpose set forth.

25 2. A car-truss pedestal having front and rear walls connected by union-bars, with sockets at the outer sides of the latter for the reception of the ends of the strut and stay-bar, substantially as specified.

30 3. A car-truss pedestal provided with lugs arranged at the lower corners to form intermediate sockets, and with inclined or beveled inner bearing-faces, substantially as set forth.

35 4. A car-truss pedestal provided with lugs at the opposite lower corners extending downward, and having inclined inner faces, and with a detachable wedge-bar having inclined ends

or shoulders, and fitting between the beveled faces of the lugs, substantially as set forth.

40 5. A car-truss pedestal provided with union-bars carrying lugs having inclined inner faces, and perforated to receive bolts connecting the wedge-bar to the pedestal, substantially as set forth.

45 6. A car-pedestal having union-bars, carrying lugs with beveled edges, and a wedge-bar with inclined edges abutting against the edges of the lugs and crossing the open jaws of the pedestal, substantially as set forth.

50 7. A car-pedestal provided with lugs at the opposite or lower corners having inclined lower faces, and a union-bar provided with inclined faces bearing against those of the lugs, and with a tongue, m , extending between the lugs, substantially as set forth.

55 8. A car-pedestal provided with bearings for a wedge-bar having lugs n , substantially as set forth.

60 9. A car-pedestal provided with beveled bearing-faces upon the opposite jaws, and with a wedge-bar having beveled ends and fitting between the said bearing-faces, substantially as set forth.

65 10. A car-truss pedestal provided with stiffening flanges above the bed-plate, and with front and rear walls connected by union-bars, carrying lugs with inclined inner faces, and with bearings at the inner edges of the union-bars for receiving between them a wedge-bar, substantially as set forth.

70 In testimony whereof I have signed my name to this specification in the presence of two sub-
scribing witnesses.

75 JOHN STEPHENSON.
